CLAIM

We claim the ornamental design for a fastening nut, as shown and described.

DESCRIPTION

FIG. 1 is a perspective view of a fastening nut according to one embodiment.

FIG. 2 is a first side view of the fastening nut of FIG. 1. FIG. 3 is a second side view of the fastening nut of FIG. 1. FIG. 4 is a third side view of the fastening nut of FIG. 1. FIG. 5 is a fourth side view of the fastening nut of FIG. 1. FIG. 6 is a first end view of the fastening nut of FIG. 1. FIG. 7 is a second end view of the fastening nut of FIG. 1. FIG. 8 is a perspective view of a fastening nut according to another embodiment.

FIG. 9 is a first side view of the fastening nut of FIG. 8. FIG. 10 is a second side view of the fastening nut of FIG. 8. FIG. 11 is a third side view of the fastening nut of FIG. 8. FIG. 12 is a fourth side view of the fastening nut of FIG. 8. FIG. 13 is a first end view of the fastening nut of FIG. 8; and, FIG. 14 is a second end view of the fastening nut of FIG. 8. Any portion of the fastening nut shown in broken lines is included for the purpose of illustrating environment and forms no part of the claimed design.

1 Claim, 12 Drawing Sheets
